CHARLES F. LE FEVER, OF PLYMOUTH, MICHIGAN, ASSIGNOR TO DAISY MANUFACTURING COMPANY, OF PLYMOUTH, MICHIGAN, A CORPORATION OF MICHIGAN

SHOOTING AND MAGAZINE BARREL FOR AIR RIFLES

Application filed October 14, 1929. Serial No. 399,633.

The invention relates to air rifles of that type in which the shooting barrel is removably inserted within the false barrel of the gun and is also provided with an adjacent magazine barrel from which the shots are successively fed into position for firing. With such constructions it is essential that the firing barrel should be perfectly straight and true and should have a lateral aperture 5 registering with the magazine barrel for the passage of the shot. However, in commercial manufacture it frequently happens that the shooting barrel of the assembly is out of true so that the port or aperture therein does 10 not properly register with the magazine barrel. Therefore, there is a considerable percentage of loss due to the elimination of these imperfect constructions.

It is the object of the present invention to 20 obtain a construction of combined magazine and shooting barrel which permits first of quickly removing and replacing a shooting barrel that is not true and second, of insuring 25 that the feed aperture in the shooting barrel is in exact registration with the magazine barrel. With these objects in view the invention consists in the construction as hereinafter set forth.

In the drawings:

30 Figure 1 is a longitudinal section through the false barrel showing a shooting barrel and magazine unit in engagement therewith;

Figure 2 is a perspective view of the unit removed;

35 Figure 3 is a cross section on line 3—3 of Figure 1;

Figure 4 is a similar cross section showing the parts in a different position of adjustment, and

40 Figure 5 is a cross section on line 5—5 of Figure 1.

As illustrated, A is the false barrel of the gun, B is the removable shooting barrel unit which is provided with a cap member C for fitting into the forward end of the false barrel and a plug D for engagement with the piston abutment E within the false barrel. Intermediate the cap C and plug D is a member F formed up from sheet metal and a 45 which constitutes the magazine barrel and a

support or re-enforcement for the shooting barrel G. The member F is formed with a segment F' which is concentric with the axis of the shooting barrel G and is of a diameter to receive said barrel telescopically. At opposite ends of this portion are extensions F² and F³ for engaging the cap C and plug D. Thus the shooting barrel G may be inserted through one end and telescoped with the member F' to extend the entire length there- 55 of.

In addition to the segment F' the member F is provided with a segment F⁴ which is about a parallel axis external to the shooting barrel and which therefore forms a magazine for holding the shot. This magazine contains a follower H which is actuated by a spring I to press the series of shot within the magazine toward the plug end of the barrel where they are successively fed to the shooting barrel through a lateral aperture G' therein. The follower is provided with a projecting ear H' which extends through the slot between the segment F⁴ and the segment F' so as to be operable for retracting the said follower to permit of loading the magazine. This loading is effected through an aperture J in the segment F⁴ and a notch K in the segment serves for engagement with the ear H' to hold the latter in retracted position, these parts being of usual construction.

With the construction as thus far described it is evident that the shooting barrel may be inserted within the member F during 85 the original assembly of the unit and if subsequently it is found that this shooting barrel is not true it can be removed and replaced by another barrel. It is, however, necessary that the aperture G' in the shooting barrel 90 should exactly register with the magazine as otherwise the feeding of the shot from the magazine to the barrel would not be possible. This where the aperture is made in the shooting barrel before assembly involves care in 95 assembly and in holding the barrel in exact position while it is being rigidly attached by solder or otherwise. Thus as has been previously stated there is considerable loss in commercial manufacture through failure 100

of the workmen to effect this exact registration.

With the present invention I have avoided possibility of this defect by drilling the aperture G' subsequent to the insertion of the barrel G within the member F' . This, however, involves the leaving of an opening L in the magazine barrel for the insertion of the drill which forms the aperture G' and further involves the necessity of closing this aperture L to prevent the shot from falling out through the same. I have accomplished the desired result by surrounding the flange D' of the plug D with a revoluble ferrule M which has a segmental portion N' extending laterally to cover the aperture L and being cut away in another portion for registration with said aperture during the operation of drilling the aperture G' . The ferrule M may be conveniently formed of slightly resilient sheet metal fashioned into segmental form and of a size to embrace the flange D' of the plug with sufficient pressure to be frictionally held in its position of adjustment. To retain the ferrule from endwise displacement upon the flange D' the latter is provided with a peripheral groove D^2 while the ferrule is formed with a plurality of indentations M^2 which engage this groove and are guided thereby. Thus in the assembly of the unit the shooting barrel G is inserted within the segment F and is secured by soldering or otherwise prior to the formation of the aperture G' . The aperture G' is then formed by a drill inserted through the aperture L after which the ferrule M is adjusted to a position where the segment M' covers the aperture L . This method of construction avoids any possibility of lack of registration of the aperture G' and the magazine barrel and in case that the magazine barrel is found upon inspection to be defective or untrue it may be easily removed, a new barrel inserted and an aperture G' drilled therein. When such a replacement is made of the shooting barrel the ferrule M may be rotated a sufficient distance to uncover the aperture L thereby permitting the insertion of the drill. To hold the ferrule in its normal position it is preferably provided with the indentation N which engages a notch O in the member D .

What I claim as my invention is:

1. The method of forming the combined magazine and shooting barrel assembly which comprises forming the magazine barrel with a portion for telescopically receiving the shooting barrel and with an aperture in the magazine portion thereof in alignment with the position for the shot feeding aperture in the shooting barrel, telescopically engaging the shooting barrel with the said portion of the magazine barrel and rigidly securing the same in this position, drilling the shot feeding aperture in said shooting barrel subse-

quent to its telescopic insertion by a drill inserted through the aligned aperture in the magazine portion and subsequent closing of said aperture in the magazine barrel.

2. A combined shooting and magazine barrel unit comprising a member formed from sheet metal constituting the magazine barrel and a re-enforcement and holder for the shooting barrel, the magazine portion being provided with an aperture in alignment with the position for the shot feeding aperture in the shooting barrel, a shooting barrel telescopically engaged with said re-enforced and holding portion, a flanged plug at the inner end of the unit for engagement with the piston abutment and a ferrule rotatively engaging the flange of said plug having a portion for covering the said aperture in said magazine barrel.

3. A combined shooting and magazine barrel unit comprising a member formed from sheet metal constituting a magazine barrel, a re-enforcement and holder for the shooting barrel, the magazine portion being provided with an aperture in alignment with the position for the shot feeding aperture in the shooting barrel, a plug secured to said member for engaging the piston abutment of the gun, said plug having a peripherally grooved flange, a magazine barrel telescopically engaging with said re-enforcing and holding portion and a spring ferrule embracing the flange of said plug having indentations for engaging the groove in the flange to prevent longitudinal displacement while permitting of rotative adjustment, said ferrule having a laterally projecting portion which in one position of adjustment covers the aperture in said magazine barrel.

In testimony whereof I affix my signature.
